UNITED STATES PATENT OFFICE

151,301

DESIGN FOR A COMBINED WRIST WATCH AND STEM GUARD

James A. Tuffo, Boston, Mass.

Application July 5, 1947, Serial No. 140,099

Term of patent 14 years

(Cl. D42—8)

To all whom it may concern:

Be it known that I, James A. Tuffo, a citizen of the United States of America and a resident of the city of Boston, county of Suffolk, Commonwealth of Massachusetts, have invented a new, original, and ornamental Design for a Combined Wrist Watch and Stem Guard, of which the following is a specification, reference being had to the accompanying drawing, forming part thereof.

Fig. 1 is a face view of a combined wrist watch and stem guard, showing my new design.

Fig. 2 is a side elevational view of same.

I claim:

The ornamental design for a combined wrist watch and stem guard, substantially as shown.

JAMES A. TUFFO.
